SEALED HOUSING FOR X-RAY TUBES

Edwin R. Goldfield, University Heights, and Edward B. Graves, South Euclid, Ohio, assignors to Picker X-Ray Corporation Waite Manufacturing Division, Inc., Cleveland, Ohio, a corporation of Ohio

Application November 2, 1942, Serial No. 464,164

4 Claims. (Cl. 250—89)

This invention relates to improvements in housings for X-ray tubes, and more particularly to novel means for tightly sealing a necessary joint in the housing together with means for preventing easy access to the housing by the user.

One of the objects of the present invention is to close the normally open end of a tube housing by novel means which provides a very good seal against the loss of oil or other fluid from the housing.

Another object of the present invention is to provide a novel means for closing the X-ray tube housing in a more or less permanent manner so that it is difficult if not almost impossible for the ordinary user to obtain access to the housing, but instead the equipment must be sent back to the manufacturer for repairs. This insures better care and expert maintenance of the equipment involved.

Other objects and advantages of the present invention will appear from the accompanying description and drawing and the essential features will be summarized in the claims.

In the drawing, Fig. 1 is a side elevational view of a tube housing equipped with our improved joint and sealing means, with a portion thereof being broken away to more clearly illustrate the location of the improved construction; Figs. 2 and 3 are enlarged fragmental sectional views taken approximately along the line 3—3 of Fig. 1, Fig. 2 showing the parts of the improved joint as assembled and before the bending of the sealing ring into final position; while Fig. 3 shows the position of the parts after the clamping and sealing operation is completed.

We have illustrated our invention as applied to an X-ray tube housing of the general character shown in Patent No. 2,259,037, granted October 14, 1941, to Edward B. Graves. It will be understood by those skilled in this art that such housings are often filled with oil or other fluid for the purpose of cooling the tube or for some other purpose. It is therefore quite often desirable that the housing be sealed in a fluid- or liquid-tight manner.

Referring now to Fig. 1, a main housing indicated at 10 encloses a tube indicated generally in broken lines at 11. The wire connections for this tube enter through the sleeves 12 and 13. A casing 14 is indicated spaced from the housing 10 through which air is blown from an electrically driven fan encased in the housing por-

tion 15. This has no connection, however, with the present invention.

As will be noticed from the various views, the housing 10 is open at the end 10a and generally at the opposite end also so that the tube 11 may be inserted into the main housing or removed therefrom through the open end. It is desirable, however, that such maintenance work on the X-ray tube be done by the manufacturer only and therefore one of the objects of the present invention is to so close the open end of the main housing that it will be difficult or almost impossible for the average user to open the housing, but instead the same must be returned to the manufacturer for repairs to the tube.

At the open end 10a the main housing is of generally cylindrical form and is provided with a flange 10b extending radially outwardly. The end of the housing is closed by a closure member 16 having a cylindrical wall 16a lying within the open end 10a of the main housing 10. Referring to Figs. 2 and 3, it will be noted that the closure member is provided with a flange of special form. This flange is bent outwardly at 16b, then bent back and away from the end of the closure member along the portion 16c which is generally parallel to the cylindrical housing 10 and to the cylindrical wall 16a of the closure member. The flange is finally bent radially outwardly at 16d providing a flange generally parallel to the flange 10b. In assembling these parts an annular gasket 17 of plastically deformable sealing material is placed between the flanges 10b and 16d so as to seal the joint between the main housing and the closure member.

The clamping means for holding the flanges 10b and 16d together comprises an annular ring 18 of a substantially rigid material which is deformable under heavy pressure, such as steel of the order of $\frac{1}{2}$ inch thick. This sealing ring is provided with two clamping flanges 18a and 18b.

The parts are assembled in the position of Fig. 2, with the flange 18b providing a cup-shaped formation opening toward the main housing 10. The flange 18b is then spun or pressed radially inwardly to the position of Fig. 3 under a pressure preferably of the order of thirty to fifty tons. This secures the flanges 10b and 16d together in a substantially permanent relation under heavy pressure. If suitable gasket material such as Neoprene is used for the gasket 17, it is deformed as indicated at 17a in Fig. 3 so as to fill all the interstices of the joint between the

flanges 10b and 16d. It will be noted that the flange portion 16c lies very close to the end of the main housing 10 at the point 19, thus providing a close sliding fit at this point. When the parts are squeezed together as shown in Fig. 3 the gasket material flows up to this restricted point 19 and is held against easy dissipation in this direction so as to compel the gasket material to completely seal all space between the flanges 18a and 18b.

Preferably the sealing ring 18 fulfills a second purpose. It will be noted that this sealing ring is provided with an annular shoulder 18c which provides a bearing for a ring shaped hanger member 20. There is one of these at each end of the tube housing to support the tube for rotative movement about the longitudinal axis of the generally cylindrical housing 10. To hold these parts in position a finishing cap 21 is secured to the closure member 16 by the screws 22. This cap has a flange 21a which lies on the side of hanger member 20 opposite the flange 18a so that the hanger member and housing are held against any substantial relative endwise movement. It will be noted that the radially outermost face 16e of the flange 16d is knurled or otherwise roughened so that when the sealing ring 18 is clamped thereagainst the parts are held against any relative turning movement which might occur as the housing is rotated in the hanger members 20.

In actual use the housing is sealed up as indicated in Figs. 1 and 3 by the manufacturer and if at any time during the use of the equipment repairs inside the housing are necessary, it is sent back to the manufacturer who utilizes a special slitting machine to cut through the sealing ring 18 between the flanges 18a and 18b so as to permit the separation of the joint and the removal of the closure member 16. Since a special tool is necessary for this operation it is unlikely that a customer will attempt to gain access to the housing 10 to make his own repairs. This is very desirable inasmuch as skilled labor is necessary for the repair and maintenance of this type of equipment and a proper sealing of the ends of the main housing is always assured.

What we claim is:

1. An X-ray tube housing construction comprising a main housing member of generally cylindrical form and open at one end, a closure member for said open end of generally cylindrical form, one of said members lying within the other and being of sheet form having a flange bent outwardly and back upon itself at the end and then bent radially outwardly, the other of said members having a flange bent radially outwardly generally parallel to said first named radially outwardly extending flange, said bent back portion of said one flange of one member lying close to the main portion of the other member and providing substantially contacting portions there, an annular gasket of plastically deform-

able sealing material between said parallel flanges, and a ring embracing said parallel flanges and bent down upon them sufficiently to compress said gasket into said joint outside of said contacting portions.

2. An X-ray tube housing construction comprising a main housing member of generally cylindrical form and open at one end, a closure member for said open end of generally cylindrical form, one of said members lying within the other and having a flange bent outwardly and then back and away from the end and then bent again radially outwardly, the other of said members having a flange bent radially outwardly generally parallel to said first named radially outwardly extending flange, said bent back portion of said one flange of one member lying close to the main portion of the other member and providing substantially contacting portions there, an annular gasket of plastically deformable sealing material between said parallel flanges, and a ring embracing said parallel flanges and bent down upon them sufficiently to compress said gasket into said joint outside of said contacting portions, said ring having an annular shoulder providing a bearing, and a housing hanger member engaging said shoulder.

3. An X-ray tube housing construction comprising a main housing member having an open end through which said tube is removable, said open end of said housing having a cylindrical wall portion, a hollow shell of substantially the diameter of said wall portion and adapted to close said open end, said shell having a cylindrical wall portion having a sliding fit with said cylindrical wall portion of said housing, both of said wall portions having flanges turned radially outwardly, said flanges starting in common from the zone of said sliding fit and then separating to provide a space between them, sealing material in said space, and a ring embracing said flanges and clamping them against said sealing material.

4. An X-ray tube housing construction comprising a main housing member having an open end through which said tube is removable, said open end of said housing having a cylindrical wall portion, a sheet metal shell member having a cylindrical wall portion in sliding fit with said cylindrical wall portion of said housing, both of said wall portions having flanges turned radially outwardly, said flanges starting in common from the zone of said sliding fit and then separating to provide a space between them, sealing material in said space, a sheet metal ring member embracing said flanges and clamping them against said sealing material, one of said sheet metal members being formed to provide an annular shoulder for a bearing, and a housing hanger member engaging said shoulder.
